RAIL BRACE

George Arnold, Shaker Heights, Harry A. Schultz, Garfield Heights, and Edwin E. Rhoads, Solon, Ohio, assignors to Cleveland Frog & Crossing Co., Cleveland, Ohio, a corporation of Ohio

Application July 28, 1948, Serial No. 41,084

2 Claims. (Cl. 238—292)

1

This invention relates to a rail brace such as is applied to a railroad rail to resist any tendency of the rail to overturn outwardly from the center of the track and to clamp it to the tie plate or base plate (or switch plate) on which it rests, thus holding the rail against movements relative to the plate, which latter in turn is secured to a supporting tie as is well understood in the art.

Rail braces of the type contemplated by this invention are most frequently applied against the stock rails alongside split switch points, but their use is not necessarily limited to such application.

Further, braces of this type are frequently made adjustable, to compensate for variations in the dimensions of the rail, the seat for the rail and brace, in the brace itself, and also to afford a means of re-tightening the assembly after wear takes place.

Rail braces employed for this purpose generally have a portion which engages one of the sloping base flanges of the rail and the vertical web of the rail where it merges with the base flanges and a portion which engages the web beneath the rail head. Heretofore the rail braces have been secured to the base plates in rail clamping and bracing position by vertical hold-down or clamping bolts extending through the base plates and braces. Difficulty has been experienced with the rail braces in use in that the braces tend, when in track, to work downwardly of the sloping base flange of the rails and away from the web of the rails until the braces do not effectively clamp the rails to the base plates or brace the rails against tilting or moving away from the shoulder of the base plates.

Various arrangements have been employed to overcome this tendency of the rail braces to work away from the rails as, for instance, it has been usual to employ wedge members inserted between the rail braces and fixed abutments or back stops secured to the base plates, the function of the wedges being to force the braces toward the rails.

An object of the present invention is to provide a rail brace which is so constructed and is so secured to the base plate that when installed it tends at all times and under track conditions to work toward the rail rather than away from the rail, thus insuring the maintenance of the necessary clamping and bracing relationship between the brace and the rail.

Another object is to provide a rail brace which is so constructed and is so secured to the base

plate in rail engaging position that it will maintain such position automatically without the necessity of employing wedges or similar arrangements for the purpose of taking up looseness between the brace and the rail.

A further object is to provide a rail brace which is so constructed and is so secured to the base plate as to maintain itself under operating conditions in tight clamping and bracing relationship with the rail.

A further object is to provide a rail brace of improved efficiency as compared to the braces now in use and which brace when installed and in use maintains at all times its proper tight engagement with the rail and exerts on the rail the proper and desired lateral and downward bracing and clamping forces without tendency of tipping the rail.

Further and additional objects and advantages will become apparent hereinafter during the detailed description of several forms of rail braces embodying the inventive concept.

The invention contemplates constructing a rail brace and securing the same in rail clamping and bracing position in a manner such that the force exerted by the hold-down bolts of the brace produces, in addition to a vertical or hold-down clamping force, a component force tending to move the brace toward the rail and causing that portion of the brace which engages with one of the sloping base flanges of the rail to move upwardly of said base flange, as distinguished from the prior rail brace constructions wherein there is a tendency for the rail braces to move downwardly of the sloping base flange of the rails and work loose from proper and effective rail clamping and bracing position.

Several different forms of rail braces embodying the inventive concept are illustrated in the accompanying drawings wherein,

Fig. 1 is a transverse sectional view through a rail mounted on a base plate and clamped and braced thereagainst by a form of rail brace embodying the invention, said base plate and rail brace being shown in elevation.

Fig. 2 is a transverse horizontal sectional view of the rail shown in Fig. 1, with the rail brace and base plate shown in plan, one of the cap nuts being removed and its hold-down bolt shown in section.

Fig. 3 is a side elevational view of the rail, rail brace and base plate shown in Figs. 1 and 2, with the base plate shown as positioned on a railway tie.

Fig. 4 is a transverse vertical sectional view

through a railway rail and a modified form of rail brace embodying the invention, with the base plate shown partially in elevation and partially in section.

Fig. 5 is a horizontal sectional view through the rail of Fig. 4 and shows the rail brace and base plate of Fig. 4 in plan, with one of the cap nuts and its associated spring washer and plate washer removed from one of the hold-down bolts and the latter shown in section.

Fig. 6 is a view similar to Fig. 1 but illustrating a third form of rail brace construction embodying the invention.

Fig. 7 is a view of the rail brace shown in Fig. 6 and is partially in plan and partially in horizontal section.

Fig. 8 is a detached detail plan view of the wedge employed with the brace of Figs. 6 and 7, and

Fig. 9 is a detached detail plan view of the fixed abutment or back-stop employed with said wedge of Figs. 6 to 8 inclusive.

The form of rail brace illustrated in Figs. 1 to 3 inclusive and embodying the invention will first be described. The rail brace is employed with a railway rail indicated generally at 10 and comprising the usual base flanges 11 provided on their upper sides with downwardly sloping surfaces 12. A vertically extending web 13 interconnects the rail base with the rail head 14. The outer surfaces of the web 13 merge on a radius into the sloping surfaces 12 of the base flanges and into the underside of the rail head 14 as is well understood in the art. The rail is supported on a base plate 15 which in turn is secured to a tie 16 all as is fully known in the art. The base plate 15 on its upper side is provided with a recess in which the base of the rail is located, with the left hand side of the rail base engaging the base plate at the left hand end of the recess as viewed in the drawings. In the form shown in Figs. 1 to 3 inclusive a fixed abutment member or back-stop 17 is secured in the recess of the base plate at the right hand end of said recess by suitable securing means such as the rivets 18 as is common practice in the art.

The rail brace of Figs. 1 to 3 inclusive is for the purpose of clamping and bracing the rail in proper position to the base plate with the left hand (as viewed in the drawing) base flange of the rail firmly in engagement with the left hand end of the recess in the base plate and to prevent relative movements of the rail with respect to the base plate. This is the usual function of a rail brace as already explained.

The rail brace comprises a brace block, indicated generally by the letter B, and this block may be formed as a casting, forging or in any suitable manner as will be well understood. The brace block B comprises a vertically extending portion 19 which has at its upper end a rail engaging portion 20 that is adapted when the brace is applied to the rail to engage the side of the web 13 of the rail below but adjacent to the underside of the rail head 14, it being noted that clearance indicated at C is provided between the upper surface of the portion 20 and the under surface of the rail head for the purpose that the portion 20 will exert force against the web 13 of the rail in substantially a horizontal direction and will not exert upward force on the rail head which would tend to tip the rail. The vertical portion 19 and the rail engaging portion

20 of the block B extend longitudinally of the rail and brace.

The block B is provided with a substantially horizontal portion 21 integrally connected to the lower end of the vertical portion 19. This horizontal portion 21 adjacent to the vertical portion 19 is provided on its underside with an inclined surface 22 that engages the downwardly sloping surface 12 of the base flange 11 of the rail and has the same or substantially the same angle of inclination as the surface 12. The inclined surface 22 merges into a curved surface at the lower end of the vertical portion 19 and it will be noted that clearance C' is provided between such curved surface and the rail and also between the web 13 of the rail and the vertical portion 19 of the block below the rail engaging portion 20. In other words, the block B engages the rail only at the portion 20 and at the contacting surfaces between the inclined surface 22 of the block and the sloping surface 12 of the base flange of the rail.

The underside of the horizontal portion 21 of the block has a horizontal surface 23 extending from the inclined surface 22 to a downwardly extending rib portion 24, the right hand end of which rib portion, as viewed in the drawings, is inclined transversely of the block B and the base plate 15. The horizontal portion 21 of the block B beyond the rib 24 is provided with an overhanging lip 25 which lip on its underside is provided with a series of serrations or teeth 26 transversely disposed with respect to the lip and extending substantially throughout the longitudinal length thereof for a purpose later to be pointed out. The vertical portion 19 and the horizontal portion 21, including the lip 25, are connected by integral side walls 27 and 28, the upper surfaces of which are formed with a concave curvature extending from the portion 20 to the lip 25.

The horizontal portion 21 of the block intermediate the side walls 27 and 28 is provided with a pair of spaced openings 29 which are elongated in a direction toward the vertical portion 19. The openings 29 are for the purpose of having the hold-down bolts extend therethrough when the rail brace is clamped in operative position with respect to the rail and the base plate.

The hold-down bolts are indicated at 30 and comprise, in this instance, heads 31 located at the underside of the base plate 15 and countersunk in complementary portions of openings through said base plate. The bolts 30 are illustrated as having short vertically extending shank portions 32 connected to the heads 31 and passing upwardly of the openings in the base plate 15 and connected, in turn, to angularly disposed or inclined shank portions 33 which extend upwardly through the openings 29 in the horizontal portion 21 of the block B a substantial distance above the upper surface of said horizontal portion 21. The upper ends of the angularly or inclined shank portions 33 of the bolts are threaded as indicated at 34.

A plate washer W is provided with spaced boss portions having openings therethrough to pass over the bolts 30. The underside of the plate washer W is provided with a horizontal surface 35 contacting the horizontal upper surface of the portion 21 of the block B. The plate washer W on its underside and beneath the boss portions is provided with downwardly extending lugs 36 which extend into the openings 29 in the block. The boss portions of the washer W on their up-

per ends are formed with inclined surfaces 37 that are parallel to or substantially parallel to the sloping surface 12 of the base flange 11 of the rail and to the inclined surface 22 of the block B for a purpose later to be explained.

In securing the block B in operative position heavy spring washers 38 are positioned on the bolts 30 and in engagement with the inclined surfaces 37 of the bosses of the washer W. Cap nuts 39 are then screwed down upon the bolts 30 tightly against the spring washers 38. Coil or other forms of spring washers 38 may be used on the bolts 30 for the same purpose.

The purpose of utilizing hold-down bolts of the character shown and described and of providing the inclined surfaces 37 on the washer bosses is to produce a hold-down force or pressure on the block B that provides a force component acting to urge the block B toward the rail web 13 and to cause the surface 22 on the underside 20 of the block to ride upwardly on the downwardly sloping surface 12 of the rail base flange 11.

As previously pointed out, difficulty has been experienced in the use of rail braces in that the braces have tended under the vibrations to which they are subjected in track to work loose with respect to the rail and to gradually move downwardly of the sloping surface 12 of the base flange of the rail. In studying this problem the cause thereof was determined to reside in the use of hold-down bolts and securing means for the brace which exert only a vertical hold-down force on the brace. Consequently the severe vibrations to which the brace is subjected when in track would cause the brace to work down on the sloping surface 12 of the base flange of the rail until the brace was not in tight holding and bracing engagement with the rail. The present invention has eliminated the cause of this problem by providing hold-down means for the brace of such character as to exert a component force acting to urge the brace at all times toward the rail and upwardly of the downwardly sloping surface 12 of the base flange 11 of the rail. In the embodiment of the invention currently de-

scribed this is accomplished by having the hold-down bolts 30 provided with the angularly disposed or inclined shanks 33 while the bosses of the washer W have the inclined surfaces 37 which are substantially parallel to the downwardly sloping surface 12 of the rail base flange 11 and to the inclined surface 22 of the block B. Therefore, when the cap nuts 39 are screwed down on the bolts 30 and the heavy spring washers 38 are held by the nuts against the inclined surfaces 37 of the bosses of the washer W force components are acting on the block B which not only function to hold the block down firmly against vertical movement but also function to constantly urge the block toward the rail with the surface 22 of the block riding upwardly of the surface 12 of the rail base flange 11. The block B of the rail brace when once installed will always be held in proper engagement with the rail and will exert thereon the requisite forces holding the base of the rail firmly against the base plate 15 with the left hand end of the base tightly against the left hand end of the base plate as viewed in the drawings. In addition, the portion 20 of the block will always be held tightly against the web 13 of the rail and due to the clearance C there will be no tendency for the block to produce a tilting or rocking movement of the rail since the portion 20 will exert only a horizontal pressure against the rail web which

is firmly held against the shoulder of base plate by the engagement of the surface 22 of the block with the surface 12 of the rail base flange.

As previously referred to, it has been customary in rail braces of this character to employ separate wedge means to hold the rail braces firmly against the rails. This employment of wedges was due in large measure to the tendency of the rail braces to work away from the rails as previously explained. Although the present invention does away with the absolute necessity of utilizing wedges with the rail braces the form of rail brace shown in Figs. 1 to 3 inclusive includes simply as an additional insurance against the brace loosening with respect to the rail, an elongated wedge member 40 of known construction and substantially like the wedge member shown in Arnold Patent 2,223,865, issued December 3, 1940.

The wedge member 40 is inserted between the backstop 17 and the rib 24 of the block B and beneath the lip 25. The edge of the wedge member adjacent to the backstop 17 and which engages with said backstop is straight, while its opposite edge which engages with the inclined edge of the rib 24 is inclined to cooperate with said rib edge, it being understood that when the wedge 40 is driven into position the cooperating inclined edges referred to act to urge the rail brace toward the rail. The upper surface of the wedge 40 is provided with serrations or teeth 41 which interengagingly cooperate with the serrations 26 on the underside of the lip 25 to hold the wedge in position as will be well understood in the art.

In the structural form of rail brace embodying the invention and illustrated in Figs. 4 and 5 it will be noted that no wedge member or backstop is employed, since the rail brace will always remain in proper tight relationship with the rail when once installed because of the force exerted by the hold-down means which constantly act to urge the rail brace toward the rail and upwardly of the downwardly sloping base flange of the rail.

In this form of the construction embodying the invention, the base plate 42 is provided on its upper surface with a recess 43. The base flanges 44 of the rail are located in the recess 43 with the left hand base flange engaging the left hand end of the recess, as viewed in the drawings. The base flanges 44 of the rail are provided as usual with the downwardly sloping surfaces 45 which merge into the rail web 46 while the latter merges into the rail head 47 as will be well understood.

The rail brace of this form comprises the block, indicated generally at B', and which comprises the vertical portion 48 having at its upper end the rail web engaging portion 49 while its lower end merges into a base flange engaging portion 50 that has its lower side engaging the surface 45 of the right hand base flange of the rail, as viewed in the drawing. As in the previously described form there is a clearance C between the underside of the rail head 47 and the portion 49 of the block B' and a clearance C' between the rail web 46 and the portions 48 and 50.

The portion 50 is integral with an inclined bolt receiving portion 51, the inclination of which is parallel to, or substantially parallel to, the downwardly sloping surface 45 of the base flange of the rail.

The block B' of the rail brace beyond the inclined portion 51 is provided with an integral

horizontal foot portion 52 which bears upon the base plate 42 to the right of the recess 43 as viewed in the drawings.

The inclined portion 51 is provided with a pair of openings 53 spaced longitudinally of the rail and block and elongated in direction toward the web of the rail and toward the vertical portion 48. A pair of bolts extend through the openings 53 and each bolt has a head 54 countersunk in the lower end of an opening 55 through the base plate 42 adjacent to the right hand end of the recess 43 and to the right of the right hand base flange 44 of the rail, as viewed in the drawings. The bolts are provided with shanks 56 angular relative to the heads 54 so as to extend through the openings 55 and 53 perpendicularly to, or substantially perpendicularly to, the upper surface of the block portion 51. The upper ends of the bolts are externally threaded and project well above the portion 51.

A plate washer 58 is provided with spaced openings through which the shanks 56 of the bolts extend and said washer contacts the upper surface of the inclined portion 51. Heavy spring washers 59 surround the bolt shanks 56 and engage the plate washer 58, while cap nuts 60 screwed upon the threaded ends of the bolt shanks hold the brace in clamping and bracing assembled relationship relative to the rail. The bolts, the washer 58, spring washers 59 and cap nuts 60 are located between the side walls 61 and 62 of the block and which walls are integral with the previously described portions 48, 49, 50, 51 and 52 of the block.

As in the previously described form of construction, when the rail brace is mounted in track and the cap nuts 60 are screwed down on the hold-down bolts, the hold-down force is exerted on the block B' through the spring washers 59 and plate washer 58 and the inclined portion 51 of the block and acts not only to force the block firmly against the base plate 42 and the rail base flange 44 but also produces a component constantly tending to urge the portion 50 upwardly on the downwardly sloping surface 45 of rail base flange. Consequently, the rail brace when once installed is maintained in proper and effective clamping and bracing relationship to the rail and the tendency of the brace to work downwardly of the sloping surface 45 of the base flange is overcome. It will be noted that no wedge is used in this form of construction since the brace automatically and constantly is urged toward the rail by the action of the inclined bolt shanks 56, the inclined portion 51, the plate washer 58, spring washers 59 and cap nuts 60.

The rail brace embodying the invention and illustrated in Figs. 6 to 9 inclusive differs from the construction shown in Figs. 1 to 3 inclusive, mainly in the form of wedge member employed and, therefore, the same reference characters are employed in Figs. 6 and 7 as are used to designate the corresponding elements of Figs. 1 to 3 inclusive.

In Figs. 6 and 7 the horizontal portion 21 of the rail brace block does not have on its underside the rib 24 but extends in planular form to the lip 25. The lip 25 in this modified form also is serrated on its underside and overlies and cooperates with the serrated upper surface 63 of a wedge member 64. The wedge member 64 is provided with a lateral extension 65 which underlies the horizontal portion 21 of the block B and has its free longitudinal edge in engagement with the free end of the base flange 11 75

of the rail. The extension 65 of the wedge 64 is provided with notches 66 through which the hold-down bolts extend. The right hand longitudinal edge of the wedge 64 is provided with inclined wedging surfaces 67 and 68 separated by a recess 69 and which wedging surfaces cooperate with wedging surfaces 70 and 71 formed on the adjacent longitudinal edge of a backstop 72 that is secured to the base plate 15 in the right hand end of the recess in the base plate.

It will be understood that when the rail brace of Figs. 6 and 7 is applied to the rail and the wedge 64 is in its operative position, the latter functions to hold the base flange of the rail tightly against the left hand end of the recess in the base plate 15. Likewise, it will be seen that when the rail brace is clamped and bolted down the serrations of the lip 25 and of the wedge interlock to prevent the wedge from working loose or backing out.

It will be understood that the action of the hold-down means of the rail brace of Figs. 6 and 7 is identical with the action of the hold-down means for the rail brace of Figs. 1 to 3 and that 25 a force component is created which functions to maintain the brace in proper and effective relationship to the rail and to cause the surface 22 of the brace to move upwardly of the downwardly sloping surface 12 of the rail brace flange instead 30 of downwardly thereof.

Each and all of the embodiments of the invention illustrated and described herein include a rail brace which is so constructed and secured in clamping position to the rail, that the force exerted by the hold-down bolts of the brace produces, in addition to a vertical or hold-down force, a force tending to move the brace toward the rail and causing that portion of the brace which engages with one of the sloping base flanges of the rail to move upwardly of said base flange, as distinguished from the prior rail brace constructions wherein there is a tendency for the rail braces to move downwardly of the sloping base flange of the rails and work loose from proper and effective rail clamping and bracing position.

Although several embodiments of the invention have been illustrated and described herein, it should be understood that the invention is susceptible of various modifications and adaptations. Thus, it will be apparent that the inclinations of the axes of the hold-down bolts may be varied from those shown in the drawings and other changes may be made in the form and proportions of the parts, illustrated and described within the scope of the appended claims.

Having thus described our invention, we claim:

1. A rail brace and supporting means comprising a base plate adapted to support the base flanges of a rail with one of said flanges engaging fixed abutment means on said plate, a block on said plate and having integral parts, one of which is adapted to lie adjacent to and extend vertically of the rail web and the other of which overlies said plate and is adapted to extend laterally from the rail web, said parts having portions adapted to engage the rail web adjacent to and below the rail head and the downwardly sloping upper surface of the other base flange of the rail, said other part which overlies the base plate being provided with openings elongated in a direction that is transverse to the rail web and with an upper surface that is substantially horizontal, hold-down bolts connected to said base plate and having shank portions inclined to the vertical in a direction away from said one part of said block and

extending through the openings in said other part of said block, the diametral thickness of said hold-down bolts being substantially less than the elongated length of said openings to provide for relative movement between said block and said bolts toward the web of said rail, a washer overlying said openings in said other part of said block and provided with a substantially horizontal under surface engaging the substantially horizontal upper surface of said other part of the block and with an upper surface inclined downwardly and substantially parallel to the downwardly sloping upper surface of said other base flange of the rail, said washer being provided with openings through which said bolts extend, and nuts on said bolts which when screwed down act on said inclined upper surface of said washer to produce hold-down forces on said block including a component urging said block toward said rail and upwardly on the downwardly sloping upper surface of said other base flange of the rail and relative to said hold-down bolts.

2. A rail brace and supporting means as defined in claim 1 and wherein said washer is provided on its underside with lug portions extending into said elongated openings in said other part of said block at the end of said openings which is adjacent to the rail.

GEORGE ARNOLD.
